US00D854469S

(12) **United States Design Patent** (10) **Patent No.:** **US D854,469 S**
(45) **Date of Patent:** **** Jul. 23, 2019**

(54) **VEHICLE HANDLEBAR**

(71) Applicant: **Gogoro Inc.**, Hong Kong (CN)
(72) Inventors: **Hok-Sum Horace Luke**, Mercer Island, WA (US); **Chien-Chih Weng**, New Taipei (TW); **Hsin-Wen Su**, Taipei (TW); **Song-Fu Wang**, Taipei (TW)

(73) Assignee: **Gogoro Inc.**, Hong Kong (CN)

(**) Term: **15 Years**

(21) Appl. No.: **29/565,659**

(22) Filed: **May 23, 2016**

Related U.S. Application Data

(63) Continuation of application No. 29/508,558, filed on Nov. 7, 2014, now Pat. No. Des. 828,310.

Primary Examiner — Darlington Ly

(74) *Attorney, Agent, or Firm* — Perkins Coie LLP

(57) **CLAIM**

The ornamental design for a vehicle handlebar, as shown and described.

DESCRIPTION

FIG. 1 is a front perspective of an embodiment of a vehicle handlebar showing our new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and

FIG. 8 is a bottom plan view thereof.

FIG. 9 is a front perspective view of an alternate embodiment of a vehicle handlebar showing our new design;

FIG. 10 is a rear perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The broken lines in the drawings illustrate portions of the vehicle handlebar that form no part of the claimed design.

1 Claim, 14 Drawing Sheets
